UNITED STATES PATENT OFFICE.

BENJAMIN WERTHEIMER, OF NEW YORK, N. Y.

ADJUSTABLE BANDEAU FOR LADIES' HATS.

1,086,963.

Specification of Letters Patent.

Patented Feb. 10, 1914.

Application filed May 15, 1913. Serial No. 767,827.

To all whom it may concern:

Be it known that I, BENJAMIN WERTHEIMER, a citizen of the United States, and a resident of the city of New York, borough 5 of Manhattan, in the county and State of New York, have invented a new and Improved Adjustable Bandeau for Ladies' Hats, of which the following is a full, clear, and exact description.

10 The object of the invention is to provide a new and improved adjustable bandeau for ladies' hats, arranged to enable the milliner or other person to readily increase the size of the bearing portion of the bandeau to suit 15 the head of the customer, thus insuring a proper fit of the hat on the head of the wearer.

In order to accomplish the desired result, use is made of a bandeau provided with an- 20 nular offsets or ridges approximately step-like in cross section to permit of clipping off one or more steps to provide a bandeau of a diameter fitting the wearer's head.

A practical embodiment of the invention 25 is represented in the accompanying drawings forming a part of this specification, in which similar characters of reference indicate corresponding parts in all the views.

Figure 1 is a sectional side elevation of a 30 lady's hat provided with an adjustable bandeau forming an integral portion of the rim of the hat; Fig. 2 is a sectional side elevation of a detached bandeau; and Fig. 3 is an enlarged sectional side elevation of the same 35 with one of the steps cut off.

The bandeau A shown in Fig. 1 forms an integral part of the inner edge of the rim B, and the said bandeau A is made approxi- 40 mately step-like in cross section, that is, is formed of a number of annular offsets, ridges or similar members A', A², A³, of which the vertical portion of the upper member is preferably provided with a binding C. As shown in the drawing the mem- 45 bers A² and A³ of the bandeau are approxi- mately of the same width, while the member A' is of a width greater than the combined widths of the members A² and A³. The crown D of the hat is made separable from 50 the rim B and the bandeau A, and its lower edge rests on the rim B and the lower portion fits snugly onto the exterior face of the

vertical portion of the lowermost member A' of the bandeau, as plainly indicated in Fig. 1. The bandeau A may be made, however, 55 separate from the rim B and the crown D, as shown in Figs. 2 and 3, and in this case the bandeau is provided on the lower edge with a lining C', and with a lining C² at the upper edge, the lower lining C' being fas- 60 tened by stitches or other means to the crown D of the hat so as to hold the bandeau in place in the hat. In case the uppermost member A³ of the bandeau is too small to fit the wearer's head then the milliner or other 65 person clips off the uppermost member A³, that is, the vertical and horizontal portions, so that the next member A² provides the proper size of bandeau for the wearer. In case a still larger bandeau is required, the 70 second member A² is cut off so that the vertical portion of the last member A' provides a large-sized bandeau. It is understood that the milliner, after cutting off one or more members, provides the remaining upper 75 member with a lining C so as to give the proper finish to the bandeau (see Fig. 3), which latter shows the bandeau illustrated in Fig. 2 with the upper member A³ cut off and the member A² provided with the lining 80 C². If desired, the linings C, C', C² may be reinforced, by the use of rings of wire or other material, a, attached to the upper edge of the bandeau and covered by the lining C², and attached to the lower edge of the ban- 85 deau and covered by the lining C'.
The bandeau is preferably made of an open mesh woven fabric material rendered stiff by a suitable sizing or the like to give the desired stiffness to the bandeau.

Having thus described my invention, I claim as new and desire to secure by Letters Patent:

1. As a new article of manufacture, a ban- 90 deau formed of three annular members, the members being of different diameters and secured one upon the other to give the bandeau a step-like shape in cross section, the two upper members being approximately of the same width and the lower member being of 100 a width greater than the combined width of the said upper members.

2. A hat provided with a rim, a bandeau 105 extending integrally from the inner edge of

the rim and having a series of offset annular members extending inwardly and upwardly from the said inner edge of the rim, and a lining for the vertical portion of the uppermost offset member.

5 3. A hat comprising a rim having an integral bandeau, the bandeau having a series of offset annular members, and a crown resting upon the brim and fitting the exterior

face of the vertical portion of the lowermost 10 member of the bandeau.

In testimony whereof I have signed my name to this specification in the presence of two subscribing witnesses.

BENJAMIN WERTHEIMER.
